Voorhies*Assistant Examiner* — Benjamin D. Wannemacher(74) *Attorney, Agent, or Firm* — Steve LeBlanc, LLC(57) **CLAIM**

The ornamental design for a wrench, as shown and described.

DESCRIPTION

FIG. 1 is a front perspective view of the wrench;
FIG. 2 is a rear perspective view of the wrench;
FIG. 3 is a front plan view of the wrench;
FIG. 4 is a rear plan view of the wrench; and,
FIG. 5 is a side plan view of the wrench.
The broken lines are included for the purpose of illustrating portions of the wrench and form no part of the claimed design.

1 Claim, 4 Drawing Sheets(56)
